UNITED STATES PATENT OFFICE.

DENIS A. FLAVELL, OF JERSEY CITY, NEW JERSEY, ASSIGNOR TO BERNARD COMPANY OF N. J., OF JERSEY CITY, NEW JERSEY, A FIRM COMPOSED OF THEODORE F. BERNARD AND DENIS A. FLAVELL.

FEEDING MECHANISM FOR WIRE STITCHING OR STAPLING MACHINES.

Application filed November 12, 1921. Serial No. 514,644.

To all whom it may concern:

Be it known that I, DENIS A. FLAVELL, a citizen of the United States, residing at Jersey City, in the county of Hudson and State 5 of New Jersey, have invented certain new and useful Improvements in Feeding Mechanism for Wire Stitching or Stapling Machines; and I do hereby declare the following to be a full, clear, and exact description 10 of the invention, such as will enable others skilled in the art to which it appertains to make and use the same, reference being had to the accompanying drawings, and to characters of reference marked thereon, which 15 form a part of this specification.

This invention relates, generally, to an improved machine for feeding pamphlets, book signatures, and the like to a wire stitching or stapling machine.

20 The invention has for its principal object to provide a novel, simply constructed and efficient mechanism for automatically and successively feeding pamphlets, book signatures, etc., to and upon the carrier guide of a wire stitching or stapling machine, whereby the pamphlets, book signatures, etc., are operatively submitted to the latter machine so that wire stitching or staples may be applied thereto to bind or fasten together the 30 leaves thereof.

Other objects of this invention, not at this time more particularly enumerated, will be clearly understood from the following detailed description of the same.

35 With the various objects of this invention in view, the same consists, primarily, in the novel construction of work feeding mechanism for wire stitching or stapling machines hereinafter set forth; and, the invention consists, furthermore, in the novel arrangements and combinations of the various devices and parts, as well as in the details of the construction of the same, all of which will be hereinafter more fully described, and 40 then finally embodied in the claims appended hereto.

The invention is clearly illustrated in the accompanying drawings, in which:—

Figure 1 is an end elevation of the novel 50 work feeding mechanism made according to and embodying the principles of this invention; Figure 2 is a part section and part side

elevation of the same, taken on line 2—2 in said Figure 1; Figure 3 is a plan view of the same; Figure 4 is a detail fragmentary 55 horizontal section through the discharge end of the mechanism, drawn on an enlarged scale; Figure 5 is a detail fragmentary side view and part vertical section of the said discharge end of the mechanism; Figure 6 is a fragmentary side elevation of the initial work propelling devices of the mechanism, drawn on an enlarged scale; Figure 7 is a fragmentary vertical transverse section taken on line 7—7 in said Figure 6; and, 60 Figure 8 is a detail vertical cross section of the cam device for operating the initial work propelling devices, said view being also drawn on an enlarged scale.

Similar characters of reference are employed in all of the hereinabove described views, to indicate corresponding parts.

Referring now to said drawings, the reference character 1 indicates a suitable frame-work upon which the novel work feeding 75 mechanism is mounted and supported. Secured to said frame-work, at the upper rear side portion thereof, is a longitudinal rod 2, and supported by outwardly extending brackets 3, at the rear side of said frame-work, is another similar longitudinal rod 4, which parallels the said first mentioned rod 2. Connected with and supported by said rods 2 and 4 is a fixed frame-plate 5 and an adjustable frame-plate 6, the latter being 80 movable upon said rods 2 and 4 toward or away from said fixed frame-plate 5. Extending between said frame-plates 5 and 6, at their outer ends is a pivot rod 7. Pivotedly connected by its outer end upon said 85 pivot rod 7 is a chute-frame 8 which is associated with said fixed frame-plate 5; and, in like manner, pivotedly connected by its outer end upon said pivot rod 7 is a chute-frame 9 which is associated with said adjustable 90 frame-plate 6. Said frame-plates 5 and 6 are respectively slotted, as at 10 (see Figure 1), and through said slots project from the respective chute-frames threaded studs 11, upon which are engaged clamp nuts 12. The 100 chute-frames thus mounted provide a runway or chute in which the piles of pamphlets, signatures or the like are deposited, and through which the same are moved into

operative relation to the feeding mechanism per se. It will be understood that the runway or chute thus provided is adjustable to adapt the same to the length and width of 5 the pamphlets, signatures or the like to be operated upon by the machine, and to this end the frame-plate 6 may be moved toward or away from the frame-plate 5 to adjust or dispose the chute frames to correct 10 respond to the length of the pamphlet or the like to be operated upon, and the inner ends of the chute-frames may be raised or lowered to adjust the discharge end of the runway or chute relative to the feeding 15 mechanism per se in correspondence to the width of the pamphlet or the like to be operated upon.

Mounted in said frame-work 1, so as to be located at the discharge end of the runway 20 or chute provided by said chute-frames 8 and 9, are a longitudinal row of vertical guide rollers 13, against which the pamphlets 14 massed in said runway or chute come to rest.

Journalized in the lower portion of the 25 frame-work 1, is a transversely extending main driving shaft 15, which is rotated by a belt driven pulley 16, or by any other suitable means, or in any other desirable manner.

30 Means are provided for moving the pile of pamphlets 14 through the runway or chute above described, so as to keep the inner end of said pile of pamphlets pressed against the vertical guide rollers 13. This means is 35 driven from the main driving shaft 15, and the same comprises rollers 17 fixed upon vertical spindles 18 journaled in bearings 19 connected respectively with said frame-plates 5 and 6. The said frame-plates 5 and 40 6, and also the associated chute-frames 8 and 9, possess openings which permit said rollers 17 to project into the runway or chute at the sides thereof, so as to engage and thrust forward the pile of pamphlets deposited 45 therein. Journalized in bearings provided in connection with said brackets 3 is a longitudinal shaft 20 upon which are mounted bevel gears 21 which mesh with bevel gears 22 fixed on the lower ends of said spindles 18. The transmission means intermediate 50 said main driving shaft 15 and said shaft 20 comprises a vertical shaft 23 which is journaled in bearings connected with the frame-work 1. Fixed on said main driving shaft is a bevel gear 24 which meshes with a bevel gear 25 fixed on the lower end of said vertical shaft 23. Fixed on the upper end of said vertical shaft 23 is a worm 26 which meshes with an idler gear 27, which in turn 55 drives a spur gear 28 fixed on the end of said shaft 20.

Fixed on the rearward end of said frame-work 1 is an upwardly projecting bracket 29 provided at its upper free end with a longitudinal guide member 30 stationed in rear-

wardly spaced relation to the rear end of said row of vertical guide rollers 13. Mounted in said guide member 30, so as to be capable of longitudinal reciprocatory movement therein, is a slide bar 31, to the forward end 70 of which is secured a push-piece 32. Secured upon the upper end or top side of said push-piece 32 is an expander member 33 which is provided at its forward end with a cam-nosing 75 34. Said cam-nosing 34 projects beyond and overhangs the forward end of said push-piece 32, and the same is provided on its under side and extending rearwardly from its free end, with a downwardly and rearwardly inclined cam-surface 35. Said expander member 33 is adjustable laterally upon said push-piece 32, and to this end the same is provided with a transverse slot 36 through which extends the fastening screw 37 which secures the said expander member 80 to the push-piece. Associated with said slide bar 31 is a lateral stud 38. For purposes which will presently appear, said stud is arranged for longitudinal adjustment on said slide-bar, and to this end said slide-bar is 85 provided with a longitudinal slot 39 through which the threaded shank 40 of said stud extends. A locking nut 41 screws on said shank 40 so as to bind the stud in desired adjusted position on the slide-bar. The 90 means for reciprocating said slide-bar 31, and the parts carried thereby, comprises a bell-crank 42 which is pivotally connected with or mounted on said frame-work 1. The vertical arm 43 of said bell-crank terminates 95 in a forked or bifurcated portion 44 which straddles said lateral stud 38 so as to operatively engage the same. The horizontal arm 45 of said bell-crank extends toward said main driving shaft 15. Connected with the 100 free end of said horizontal arm 45 is a transverse stud or roller 46. Fixed on said main driving shaft 15 is a cam-wheel 47, provided in one face with a cam-groove 48 in which is operatively received said stud or roller 46. The rotation of said cam-wheel 47 operates, 105 through said cam-groove 48 which engages the stud or roller 46, to oscillate said bell-crank 42, thereby transmitting to said slide-bar 31, and the parts mounted thereon, a 110 longitudinal reciprocatory movement.

Adjustably connected with said frame-plate 6, in line with said expander member 33, is a gauge piece 49, which may be adjusted outwardly or inwardly, according to 115 the thickness of the pamphlet 14 to be operated upon, and which serves as a gauge for determining the amount of lateral adjustment of the expander member 33 necessary to be made to properly align the latter with 120 the pamphlet 14.

Mounted in connection with a suitable bearing frame or bracket 50 supported at the forward end of said frame-work 1, are a pair of vertical propelling rolls 51. Said 130

rolls 51 respectively turn in opposite directions, and run in contact one with the other, the outer roll being laterally yieldable by reason of its being journaled in spring backed yieldable bearings 52. Said rolls 51 are positioned adjacent to and opposite the forward end of said row of guide rollers 13, so as to receive a pamphlet 14, when it is moved longitudinally forward along said 10 guide rollers 13 to pass between said rolls 51, whereby the said pamphlet is gripped by the latter and fed forwardly and outwardly thereby. Each roll 51 is provided at its lower end with a gear 53, said gears 53 in 15 termeshing one with the other. The means for producing the rotation of said rolls 51, comprises a vertical shaft 54 journaled in said frame 1; the upper end of said shaft 54 carries a gear wheel 55 which meshes with 20 one of said gears 53, and the lower end of said shaft 54 carries a bevel gear 56, which meshes with and is driven by a bevel gear 57 mounted on said main driving shaft 15.

Mounted on the inner end of said frame- 25 plate 5, so as to be opposed to the forward end of said row of guide-rollers 13, and intermediate the latter and said propelling rolls 51, is a vertical guide roller 58, which aids in guiding a forwardly moved pamphlet to and between the propelling rolls 51.

The reference character 59 indicates a vertically yieldable forwardly projecting arm which is pivotally secured between bearing ears 60 supported on said frame or bracket 35 50. Said arm 59 is provided at its free end with perforated lugs 61 for supporting a transverse axle 62 upon which is mounted an annularly grooved expander wheel 63. Said arm 59 overhangs the upper ends of the 40 propelling rolls 51, intermediate the latter, and somewhat forwardly spaced therefrom, so that the expander wheel 63 will engage the upper forward end of the folded edge of the pamphlet 14 as the same issues outwardly from between the said rolls 51. A leaf- 45 spring member 64 secured to said lugs 61 bears with its free end upon the outer end of said arm 59, so as to place said arm 59, and the expander wheel 63 mounted in connection therewith, under an upwardly yielding 50 tension.

Secured to the forward end of said frame-work 1 is a forwardly projecting upturned bracket or post 65 upon which is supported 55 the receiving end of a guide-rail 66 which leads to the wire stitching or stapling mechanism (not shown). This guide-rail 66 is of inverted V-shape in cross-section, and its receiving end tapers rearwardly to provide a sharp spur or finger 67, located adjacent to 60 and in line with the expander wheel 63. Said spur or finger enters the expanded end of the pamphlet 14, as the latter is fed outwardly by the rolls 51, so that the pamphlet 65 rides on its center fold forwardly upon said

guide-rail. The inverted V-shape of the guide rail, when the pamphlet rides onto the same, tends to open out the two halves of the pamphlet from the center fold thereof, so that the center fold is supported in a proper manner for the insertion there-through of the wire-stitches or staples which are to bind the pamphlet leaves together.

Associated with said guide-rail 66, adjacent to its receiving end are a pair of propelling wheels, comprising an upper driven wheel 68 having a periphery concave in cross-section, and a lower idler wheel 69 having a periphery convex in cross section. Said idler wheel 69 is mounted on an axle 70 supported between the bearing portions 71 formed at the under side of the walls of said guide-rail; the guide-rail 66 is cutaway to permit the periphery of said idler wheel 69 to project slightly above the top edge surface of the same. The means for mounting the upper driven wheel 68 comprises a pair of laterally spaced arms 72, which respectively project upwardly on either side of said guide-rail 66, and outwardly spaced 80 from the latter so as to permit the pamphlets to readily pass between the same when they ride onto said guide-rail. The upper ends of said arms 72 provide bearings for journaling a transverse spindle 73 upon 85 which said driven wheel 68 is mounted. Said spindle is arranged to yield upwardly by reason of one end thereof being journaled in a vertically movable bearing block 74 connected with one arm 72 and held under the tension of a spring 75, thus permitting the driven wheel 68, which contacts with said idler wheel 69, to yield to the passage of a pamphlet between said wheels. Connected with said spindle is a pulley 76, 100 over which runs a driving belt 77, driven by a pulley 78 fixed on said main shaft 15, so that the rotation of said main shaft is transmitted to the spindle 73 to rotate said driven wheel 68. An idler pulley 79 mounted on the 105 side of said bracket 65, so guides said belt 77 as to permit it to run under the framework 1. After the pamphlet is delivered free of the rolls 51 and on to the guide-rail 66 the propelling wheels 68 and 69 grip and feed 110 the same forward on the guide rail, each succeeding pamphlet pushing on the one ahead, so that a train of pamphlets moves over the guide rail to be successively operated upon by the wire stitching or stapling 115 mechanism to which said guide rail leads.

In operation, the pamphlets 14 are loaded into the runway or chute so that they stand on edge with their folded edge uppermost. The pamphlets thus disposed in the runway 120 or chute continually move forward so as to hold the innermost pamphlet upright against the row of guide-rollers 13. The gauge piece 49 is adjusted so as to be spaced from the plane of the supporting faces of 125 130

the guide-rollers a distance equivalent to the thickness of one pamphlet. When the gauge piece 49 is thus adjusted, the expander member 33 is adjusted on the push-piece 32 so that its inner longitudinal edge is alined with the outer face of the gauge piece 49, thus arranging the expander member so as to engage and operate only upon the one or innermost pamphlet. As shown in the drawings, the runway or chute is adjusted to hold pamphlets of maximum length, and the slide-bar 31 is adjusted, relative to the bell-crank 42, to position the push-piece 32 and expander member 33 for proper cooperation with the pamphlet of maximum length. If a pamphlet of less length is to be dealt with, the adjustable side of the runway or chute is moved toward the fixed side thereof, to reduce the width of the runway or chute to correspond with the pamphlet of less length. The guide-rollers 13 are removable, and since the length of the row of guide-rollers 13 must be reduced proportionately to the reduced length of pamphlet, a sufficient number of said guide-rollers at the rearward end of the row of the same are removed to accomplish this result. The push-piece 32 and expander member 33 must be adjusted forwardly so as to be placed in position to immediately engage the pamphlet of less length, when the operative forward stroke of said parts is initiated. To this end the stud 38 is loosened relative to the slide-bar 31, to permit the latter to be moved forward to carry the push-piece 32 and expander member 33 to the proper adjusted normal initial position. When such adjustment is attained, the stud 38 is secured again, and the machine is ready for operation. The stroke of the push-piece 32 is always the same, whether the machine operates upon pamphlets of maximum length or upon pamphlets of less than maximum length. It will thus be apparent that by the above described adjustments the machine may be readily prepared to operate upon pamphlets of various sizes and thicknesses, between certain predetermined maximum and minimum limits.

The machine having been duly adjusted as conditions require, power is applied to rotate the main driving shaft 15, and through the various transmission mechanisms, to operate the several moving parts of the machine. The operation of the bell-crank 42 causes a forward movement of the slide-bar 31. This forward movement of the slide-bar first carries the cam-nosing 34 of the expander member 33 into engagement with the rearward end of the upper folded edge of the inner-most pamphlet, so that the cam-surface 35 produces a downwardly pushing pressure upon such portion of said pamphlet. The downwardly pushing pressure thus exerted expands the folded edge of the pamphlet thereby producing an outward sidewise bulge X (see Figure 7) as such portion of the pamphlet, thus widening the upper end of the latter so as to assure an end surface against which the push-piece 32 may thrust, and at the same time assuring that only the innermost pamphlet will be engaged and thrust upon by said push-piece. By the time the bulge X is formed, the forward movement of the slide-bar will move the push-piece 32 into engagement with the said bulged end of the innermost pamphlet, and the push-piece 32 continuing its forward movement will thrust the pamphlet endwise and forwardly along the guide-rollers 13. The endwise or longitudinal forward movement thus imparted to the pamphlet, causes its opposite or forward end to move between and into engagement with the propelling rolls 51. Since the propelling rolls 51 are rotating, they will grip the pamphlet thus thrust between the same, and will thereupon feed the same forwardly and outwardly toward the spur or finger 67 of the guide rail 66. As the forward end of the pamphlet issues outwardly from the rolls 51, the forward end of the upper folded edge thereof is carried beneath and into engagement with said expander wheel 63, which exerts a downward pressure upon said folded edge to expand or open up the same from the center of the pamphlet, thus forming a loop y (see Figure 5) which permits the folded edge of the pamphlet to ride over and upon the finger 67 of the guide-rail 66. As the pamphlet is thus caused to ride on to the guide-rail 63 the propelling wheels 68 and 69 grip and propel the pamphlet forwardly upon the rail 66 when released from the rolls 51.

The operative stroke of the push-piece 32 being completed, the same is retracted so that as the succeeding operative stroke occurs the above described operations are repeated upon the succeeding pamphlet, and consequently the pamphlets are successively withdrawn from the runway or chute, and successively deposited upon the guide rail 66 to form a train of pamphlets constantly moving forward into operative relation to the wire-stitching or stapling mechanism with which my novel feeding mechanism is associated.

It will be evident from the above description that my present invention provides a very simple and efficient automatic mechanism for successively feeding forward and opening up pamphlets, book signatures and the like, with their folded edges properly presented to receive wire-stitching, staples or similar fastening means for binding the leaves thereof together.

I am aware that some changes may be made in the arrangements and combina-

tions of the various devices and parts as well as in the details of the construction of the same, without departing from the scope of my invention as set forth in the foregoing specification, and as defined in the appended claims. Hence, I do not limit my invention to the exact arrangements and combinations of the various devices and parts as described in said specification, nor do I confine myself to the exact details of the construction of said parts as illustrated in the accompanying drawings.

I claim:—

1. In a mechanism of the kind described, the combination with a propelling means of means for delivering pamphlets or the like endwise thereto with their folded edges uppermost, a guide rail to which said pamphlets are delivered by said propelling means, and means intermediate said propelling means and said guide rail for expanding the forward portion of the folded edge of each pamphlet as it issues from the propelling means to permit the same to enter upon and straddle said guide-rail.

2. In a mechanism of the kind described, means for supporting pamphlets or the like massed together on edge with their folded edges uppermost, a propelling means, means for successively delivering pamphlets endwise from said mass to said propelling means, a guide rail to which said pamphlets are successively delivered by said propelling means, and means intermediate said propelling means and the receiving end of said guide rail for expanding the forward portion of the folded edge of each pamphlet to permit the latter to enter upon and straddle said guide-rail.

3. In a mechanism of the kind described, a chute device for holding pamphlets or the like massed together on edge with their folded edges uppermost, a propelling means, means for successively delivering pamphlets endwise from the inner end of said mass thereof to said propelling means, a guide rail having its receiving end adjacent to said propelling means, and means intermediate said propelling means and said guide rail for expanding the forward portion of the folded edge of each pamphlet to permit the latter to enter upon and straddle said guide-rail.

4. In a mechanism of the kind described, a chute device for holding pamphlets or the like massed together on edge with their folded edges uppermost, a propelling means, means for successively delivering pamphlets endwise from the inner end of said mass thereof to said propelling means, a guide rail having its receiving end adjacent to said propelling means, and means intermediate said propelling means and said guide rail for expanding the forward portion of the folded edge of each pamphlet to permit the latter

to enter upon and straddle said guide-rail, and a second propelling means associated with said guide-rail for feeding forward in a train the pamphlets delivered upon said guide-rail.

5. In a mechanism of the kind described, a chute device for holding pamphlets or the like massed together on edge with their folded edges uppermost, a propelling means, means for successively delivering pamphlets endwise from the inner end of said mass thereof to said propelling means, a guide-rail upon which said pamphlets are successively delivered by said propelling means, and an upwardly yieldable expander wheel mounted to overhang the discharge side of said propelling means adapted to expand the forward portion of the folded edge of each pamphlet issuing from said propelling means thereby permitting the same to enter upon and straddle said guide-rail.

6. In a mechanism of the kind described, a chute device for holding pamphlets or the like massed together on edge with their folded edges uppermost, a propelling means, means for successively delivering pamphlets endwise from the inner end of said mass thereof to said propelling means, a guide-rail upon which said pamphlets are successively delivered by said propelling means, an upwardly yieldable expander wheel mounted to overhang the discharge side of said propelling means adapted to expand the forward portion of the folded edge of each pamphlet issuing from said propelling means thereby permitting the same to enter upon and straddle said guide-rail, and a second propelling means associated with said guide-rail for feeding forward in a train the pamphlets delivered upon said guide-rail.

7. In a mechanism of the kind described, the combination with a pair of opposed vertical propelling rolls of means for delivering pamphlets or the like endwise thereto with their folded edges uppermost, a guide rail to which said pamphlets are delivered by said propelling rolls, and an upwardly yieldable expander wheel mounted to overhang the discharge side of said propelling rolls adapted to expand the forward portion of the folded edge of each pamphlet issuing from said propelling rolls to permit the same to enter upon and straddle said guide-rail.

8. In a mechanism of the kind described, the combination with a pair of opposed vertical propelling rolls of means for delivering pamphlets or the like endwise thereto with their folded edges uppermost, a guide rail to which said pamphlets are delivered by said propelling rolls, an upwardly yieldable expander wheel mounted to overhang the discharge side of said propelling rolls adapted to expand the forward portion of

the folded edge of each pamphlet issuing from said propelling rolls to permit the same to enter upon and straddle said guide-rail, and a propelling means associated with said guide-rail for feeding forward in a train the pamphlets delivered upon said guide-rail.

In testimony that I claim the invention set forth above I have hereunto set my hand this 4th day of November, 1921.

10
